(57) **CLAIM**

The ornamental design for a LED 5 in 1 stage light, as shown and described.

DESCRIPTION

FIG. 1 is a perspective view of a LED 5 in 1 stage light showing my new design;

FIG. 2 is an alternative perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in drawings are included for the purpose of illustrating portions of the LED 5 in 1 stage light, and form no part of the claimed design.

1 Claim, 8 Drawing Sheets
